Goodwin & Pitts, Jr.,
Design for a
Stove.

Patented Dec. 10th 1846.

C. Goodwin & W. Littlejohn New York, New York
Letter Patent (Design No. 101) dated 10th December 1846
Ante-dated the 11th November 1846

The schedule referred to in this Letter Patent and making
part of the same.

To all whom it may concern Be it known that we, C. Goodwin and W. Littlejohn of the City, County, and State of New York, have invented or produced a new and ornamental design or configuration of a fuel cylinder stove, and which we, do hereby declare that the following is a full and exact description of the same.

The nature of our invention consists in the application to the ordinary fuel cylinder stove, of three ornamental cast or malleable iron caps, to surmount the three cylinders, and the scalloped base, with an ornamental beveling border, and supported on feet representing lions with griffin wings. These caps, see drawings, letters A A A, are cast in one piece, and so made as to fit with the top of the cylinders. On the surface, are various ornamental raised figures representing the vine and leaf, and on top surmounted by a button somewhat

in the shape of an acorn. Letter B, the base is also of cast or malleable
iron, with a scalloped form as represented in the drawing, having an
ornamental beveling, border about three inches deep, as represented by
letter C, and the whole resting, on four feet representing lions
with griffin wings as shown by letters D.D.

Somewhat is claimed and wished to be secured by letters patent
of the United States, is the particular scalloped configuration of the base,
with the border as represented by letter C attached and supporting
the four lions with griffin wings; and also the three caps as shown
by letters A.A.A, with the particular devices therein. In consequence
of mounting the entire cap, nor the ornaments on the cylinder, nor the
cylinders themselves, we do not claim, they having been known and
used prior to these improvements.
